SASH LOCK

John M. Tracy, New Britain, Conn., assignor to
 The American Hardware Corporation, New
 Britain, Conn., a corporation of Connecticut

Application February 7, 1936, Serial No. 62,722

6 Claims. (Cl. 292—336)

My invention relates to a sash lock.

It is an object of the invention to provide a sash lock which is self-locking when the sashes are moved to relatively closed position.

5 It is another object to provide a sash lock in which one of the locking parts is moved to and held in inoperative position when the sash is being raised and lowered and automatically moved into operative and locking position when 10 the sash is substantially completely closed.

It is a further object to provide a sash lock having means to be engaged for raising as well as lowering the sash.

Other objects and features of the invention 15 will be pointed out or will become apparent upon a reading of the specification.

In the drawing which shows, for illustrative purposes only, a preferred form of the invention—

20 Fig. 1 is a fragmentary top plan view of an upper and lower sash illustrating one form of my improved sash lock applied thereto;

Fig. 2 is a vertical sectional view through the sashes shown in Fig. 1 and showing the improved sash lock, parts being broken away to 25 illustrate interior construction; and

Fig. 3 is a view of the parts shown in Fig. 2 but in different relative positions and showing the sashes unlocked and separated.

30 In said drawing 5 indicates the lower portion of an upper sash, while 6 indicates the adjacent upper section of a lower sash. The improved sash lock includes a keeper and locking member to be attached to the sash parts and one of the 35 members is movably mounted so as to be moved into interlocking engagement with the other of said parts and automatically when the sash parts are moved to closed position.

In the form shown a keeper 7 is attached to 40 the upper sash 5 and is provided with a keeper portion 8. The keeper 7 is attached to the sash part 5 by suitable means, such as screws 9—9, as will be understood. The other sash section, in this case the lower sash 6, carries adjacent

45 the keeper member 7, a bracket member 10, which may be secured to the lower sash as by means of screws 11—11. A substantial hook member 12 having an upturned hooked locking nose at its inner end is pivotally mounted in the 50 bracket on the horizontal pivot pin 13 extending through the hook into the side plates 14—14 of the bracket 10. When the hook 12 is in the position shown in Fig. 2, that is, engaged with the keeper portion 8, an attempt to raise the sash 55 6 will be ineffective, since the upturned nose of

the hook engages beneath and behind the keeper part 8. The hook member 12 is provided with an outwardly extending extension or handle member 15, preferably having an eye 16 therein for engagement by a projection on a window pole 17, as will 5 be understood. When the hook extension 15 is raised either by hand or the window pole 17, it will be seen that the hook 12 will be withdrawn from the keeper 8 and moved to the position shown in Fig. 3, that is, so that the lower sash 10 may be raised.

In order to provide for automatic locking of the sash lock when the window is lowered I provide means for holding the hook 12 in inoperative position while the lower sash is in raised 15 position. In the form illustrated I employ a latch 18, pivotally mounted on a horizontal pin 19, carried by the hook member 12. The latch is provided with a latching surface or shoulder 20, to automatically engage behind the latching 20 abutment 21 carried by the bracket 10, so as to hold the hook retracted in the inoperative position shown in Fig. 3 when the window is opened. Thus, when the hook 12 is held in the inoperative 25 position of Fig. 3 the lower sash may be both 25 raised and lowered in the usual manner or by means of the handle extension 15 engaged by a window pole. The latch 18, in addition to its latching parts, has a releasing nose 22, positioned as shown in Fig. 3, to be engaged by the top camming surface 23 of the keeper 7 when the lower 30 sash is lowered. Thus it will be clear that when the lower sash is lowered the nose 22 will ride on the surface 23 and cause the latching shoulder 20 to be automatically disengaged from the latching 35 abutment 21 and the hook 12 will then move through the action of gravity or otherwise into hooking or interlocking engagement with the keeper part 8. When gravity is relied upon, the handle portion 15 and the locking means should 40 be sufficiently heavy to cause the locking device to swing from the position shown in Fig. 3 to the locking position shown in Fig. 2 when the latch 18 is released from the abutment 21.

In the preferred form illustrated I employ two 45 latch members 18 and abutments 21 at opposite sides of the hook 12, as will be seen in Fig. 1, but since the latches are preferably duplicates of each other only one has been fully shown in detail and specifically described.

50 It will be seen that with my improved sash lock the unlocking of the sashes is effected with the greatest of ease merely by raising the handle extension 15 so as to withdraw the hook from the keeper 8. The extension 15 as described may 55

be employed for raising the lower sash. When the extension 15 has been moved so as to withdraw the hook 12, the latter is automatically latched by means of the latch 18 in its retracted or unlocked position, as shown in Fig. 3. When the lower sash is lowered, either by means of the hook extension 15 or otherwise, the nose 22 of the latch 18 will engage the keeper part 23 and release the hook so that it may move into locking position behind the keeper part 8 and thus can securely lock the sash parts relatively to each other.

While the invention has been described in considerable detail and a preferred form illustrated, it is to be understood that various changes may be made within the scope of the invention as defined in the appended claims.

I claim:

1. A self locking window lock comprising, a bracket to be attached to a lower sash, a hook member pivotally mounted on said bracket and engageable with a keeper on an upper sash to interlock therewith for preventing raising of said lower sash relatively to said upper sash, and an integral handle member on said hook for raising and lowering the lower sash, and latching means for latching said hook member in inoperative position when said lower sash is raised by said handle, said latching means being engageable by said keeper for releasing said hook member when said lower sash is moved to closed position relatively to said upper sash.

2. A window lock comprising, a bracket to be attached to a lower sash, a pivotally mounted hook member carried by said bracket and interengageable with a keeper on an upper sash for locking said sashes in closed position, an extension of said hook member having an eye therein for engagement by a window pole for raising and lowering said lower sash, and latch means for latching said hook member in inoperative position when the same is moved to unlocked position by a window pole and whereby said lower sash may be both raised and lowered by a window pole with said hook member held in inoperative position, said latching means being released by and upon engagement with said keeper when said lower sash is moved to substantially its lowest position relatively to said upper sash.

3. In a window lock, a movable locking member, a bracket therefor to be carried by one window sash, a horizontal pivotal support on said bracket supporting said member intermediate its ends, an upturned hooked locking nose at the inner end of said member for engagement with and disengagement from a keeper carried by an adjacent sash, an operating handle at the opposite end of said member, and means for automatically latching said member in its disengaged position when the window is opened.

4. In a window lock, a movable locking member, a bracket therefor to be carried by one window sash, a horizontal pivotal support on said bracket supporting said member intermediate its ends, an upturned hooked locking nose at the inner end of said member for engagement with and disengagement from a keeper carried by an adjacent sash, an operating handle at the opposite end of said member, means for latching said member in its disengaged position when the window is open, said latching means being released automatically by engagement with said keeper upon the closing movement of said window to permit said member to move into window locking position.

5. In a window lock, a movable locking member, a bracket therefor to be carried by one window sash, a horizontal pivotal support on said bracket supporting said member intermediate its ends, an upturned hooked locking nose at the inner end of said member for engagement with and disengagement from a keeper carried by an adjacent sash, an operating handle at the opposite end of said member, with means for normally urging said member in a window locking direction, said means comprising a sufficiently heavy handle end to overbalance the hooked locking end.

6. In a window lock, a movable locking member, a bracket therefor to be carried by one window sash, a horizontal pivotal support on said bracket supporting said member intermediate its ends, an upturned hooked locking nose at the inner end of said member for engagement with and disengagement from a keeper carried by an adjacent sash, an operating handle at the opposite end of said member, means for latching said member in its disengaged position when the window is open, said latching means being carried by said locking member and movable into latching engagement with said bracket when said locking member has been manually disengaged from said keeper preparatory to permitting the opening of the window.

JOHN M. TRACY.
